UNITED STATES PATENT OFFICE

164,158

SLIDE PROJECTOR

Murray G. Clay, Chicago, Ill.

Application August 9, 1950, Serial No. 11,688

Term of patent 14 years

(Cl. D61--1)

To all whom it may concern:

Be it known that I, Murray G. Clay, a citizen of the United States, residing at Chicago, in the county of Cook and State of Illinois, having invented a new, original, and ornamental Design for a Slide Projector, of which the following is a specification, reference being had to the accompanying drawings, forming a part thereof.

In the drawings:

Figure 1 is a front perspective view of a slide projector, showing my new design;

Figure 2 is a rear perspective view;

Figure 3 is a side view;

Figure 4 is a front elevational view;

Figure 5 is a top plan view; and

Figure 6 is a rear elevational view.

I claim:

The ornamental design for a slide projector, substantially as shown.

MURRAY G. CLAY.
